UNITED STATES PATENT OFFICE

ANDREW J. HOLLARS, OF BLUE EYE, MISSOURI

CAN ADJUSTING OR RESHAPING MACHINE

Application filed March 22, 1930. Serial No. 438,185.

This invention relates to a can adjusting or reshaping machine, and has for one of its objects to provide a novel machine of this character through the medium of which cans 5 which, due to their dented or crushed condition, are unfit for use by canneries, may be easily and quickly restored to their original or useful condition at the canneries.

The invention has for a further object to 10 provide a machine of the character stated through the medium of which dented or crushed cans of different sizes may be restored to their original or useful condition, which shall be adapted to be operated manually, and which may be operated efficiently 15 by unskilled labor.

The invention has for a further object to 20 provide a machine of the character stated which shall be simple, durable and capable of being manufactured and sold at a low cost.

With the foregoing and other objects in view, the nature of which will appear as the description proceeds, the invention consists in the construction, combination and arrangement of parts hereinafter fully described 25 and claimed, and illustrated in the accompanying drawings, wherein:—

Figure 1 is a top plan view of a can adjusting or reshaping machine constructed in 30 accordance with my invention;

Figure 2 is a view partly in side elevation and partly in vertical section of the machine;

Figure 3 is a sectional view taken on a 35 plane extending vertically and centrally through one of the can adjusting or reshaping means, with the can partly applied to the core of such means;

Figure 4 is a similar view with the can fully applied to the core;

Figure 5 is a sectional view taken on a 40 plane extending horizontally and centrally through the can adjusting or reshaping means;

Figure 6 is a sectional view taken on the 45 vertical plane indicated by the line 6—6 of Figure 3, and

Figure 7 is a sectional view taken on the horizontal plane indicated by the line 7—7 of Figure 4.

The adjusting or reshaping machine com-

prises a table 1 which is of circular formation in plan and is supported by four equally spaced legs 2. The table 1 rests adjacent its edge upon the legs 2, and is secured to the legs by bolts 3. The legs 2 are of inverted U-form in elevation. The lower cross bars 4 of the legs 2 are adapted to rest upon a floor, bench or the like, and provide means through the medium of which the machine may be secured to its support by bolts 5. The 55 sides 6 of the legs 2 are connected adjacent their upper ends by cross bars 7, and their upper ends are outturned to provide lugs 8 for the reception of the bolts 3.

The table 1 is provided at its center with a pivot support 9 which is of annular formation in plan and extends upwardly from the table. The lower portion of the pivot support 9 is arranged in an opening 10 in the table 1, and is welded or otherwise rigidly 60 secured to the wall of the opening. The pivot support 9 is provided with a handle 11 which extends diametrically across the same, and is welded or otherwise rigidly secured to the support. An annular series of can adjusting or reshaping means 12, 12a, 12b and 12c, 65 is carried by the table 1. These means 12—12c are arranged in equally spaced relation outwardly of the pivot support 9, and the respective means are located adjacent the respective legs 2. These means 12—12c are 70 similar except as to sizes, their sizes being such as to adapt them to adjust or reshape No. 1, No. 2, No. 2½ and No. 3 cans, respectively.

Each of the can adjusting or reshaping means 12—12c comprises a cylindrical core 13 which extends upwardly from the table 1 and consists of two similar upright sections 14. The core sections 14 are provided at their lower ends with outer semi-circular flanges 15. The wall of a circular opening 16 formed in the table 1, is rabbeted to provide an annular recess 17 for the reception 90 of the lower ends of the core sections 14. The flanges 15 slidably rest upon the horizontal wall of the recess 17 and the diameter of the vertical wall of the recess is greater than the 95 diameter of the flanges 15 so as to permit the 100

core sections 14 to be adjusted radially outward with respect to each other.

The core sections 14 are held against upward displacement by a ring 18 which is recessed into the upper side of the table 1 and overlies the flanges 15, the retaining ring being secured to the table by bolts 19. The core sections 14 have inclined inner or opposing sides 20 which converge in a downward direction, and they are provided in said sides thereof with passages 21 extending vertically therethrough and provided with vertical bottom walls.

A downwardly tapered wedge 22 is arranged between the core sections 14 in contact with the inclined sides 20 of the sections, and is fixed to the upper end of a bar 23 which is slidably mounted in the passages 21. The bar 23 constitutes an operating element for the wedge 22, and is guided in its movements by the walls of the passages 21. The bar 23 is greater in length than the core sections 14 and extends downwardly through the opening 16. A lever 24 which is arranged below the table 1, is pivotally connected at one end, as at 25, to a lug 26 extending downwardly from the table and secured thereto by bolts 27. The free end of the lever extends outwardly beyond the table 1 and is arranged between the sides 6 and above the cross bar 7 of the adjacent leg 2. The lever 24 is provided between its ends with a recess 28 for the reception of the reduced lower end 29 of the bar 23, and it is connected to this end of the bar by a pivot bolt 30.

From the foregoing it will be apparent that the core 13 is of the expansible type, that it is positively expanded by the downward movement of the wedge 22, and that the wedge may be manually moved downwardly to effect the expansion of the core and moved upwardly to permit the core to be contracted through the medium of the lever 24 which is adapted to be manually operated.

When it is in contracted condition, the core 13 is smaller diametrically than the inner diameter of the dented or crushed can to be restored to its original or useful condition. After the can has been applied to the core 13 in an inverted position, the wedge 22 is moved downwardly to expand the core, with the result that the can will be restored to its original or useful condition. After the can has been restored to this condition, the wedge 22 is moved upwardly. This movement of the switch 22 releases the core sections 14 for contraction and also moves the reshaped can upwardly with relation to the core sections, to the end that the can may be readily withdrawn from the core.

The can, which is designated 31, is held in a matrix 32 during the expansion of the core 13 to effect the restoration of the can. The matrix 32 comprises two upright semi-cylindrical hollow sections 33 which are fully

open at their lower ends and closed at their upper ends. The top walls 34 of the matrix sections 33 are provided in their lower sides with semicircular grooves 35 for the reception of the upwardly extended portion of the bottom bead 36 of the can 31. The upper portions of the inner lateral sides of the matrix sections 33 are provided with semi-cylindrical recesses 37 which communicate with the grooves 35 and are provided for the reception of the outwardly directed portions of the can bead 36. The remaining or lower portions of the inner lateral surfaces of the matrix sections 33 have a diameter corresponding to the normal outer diameter of the can, and these portions surround and contact with the major portion of the side wall of the can when the matrix sections are in closed relation. The matrix sections 33 are arranged in relatively closed relation about the can 31 on the core 13, and to permit them to be moved into opened position and away from the core so as to permit the can to be applied to and removed from the core, they are carried by levers 38 which are pivotally and slidably connected to the support 9.

The levers 38 are provided with semicircular portions 39 which surround the matrix sections 33 and are formed integrally therewith. The inner ends of the levers 38 pass through openings 40 in the support 9, and are pivotally and slidably connected to the support by bolts 41 which are carried by the support and pass through slots 42 formed in and extending longitudinally of the inner ends of the levers. The outer or handle ends of the levers extend radially beyond the table 1 so as to permit them to be readily grasped when it is desired to move the matrix sections 33 inwardly and hold them in can embracing relation or when it is desired to move them into can releasing relation. The pivotal and slidable connections between the levers 38 and the support 9 permit the matrix sections 33 to be moved inwardly and outwardly or laterally with respect to the core 13, and thus adapt them to be readily moved into closed or can holding relation or into opened or can releasing relation.

From the foregoing description, taken in connection with the accompanying drawings, it should be apparent that when it is desired to restore a dented or crushed can to its original or useful condition, it is only necessary to place the can in an inverted position upon the core adapted to receive the same, then move the matrix sections 33 into closed or can holding relation, and then move the lever 24 downwardly while holding the matrix sections in their closed relation. The downward movement of the wedge 22, as the result of the actuation of the lever 24, spreads the core sections 14, the spreading of the core sections forcing outwardly any indented

or crushed portions of the can, and the matrix 32 insuring the reshaping of the can to its original condition and preventing any upward displacement thereof from the core.

5 It should also be apparent that the can restoring means 12—12c are so arranged upon the table 1 that they may be simultaneously used by different operators without one interfering with the other.

10 While I have described the principle of the invention, together with the structure which I now consider the preferred embodiment thereof, it is to be understood that the structure shown is merely illustrative and 15 that such changes may be made, when desired, as fall within the scope of the invention as claimed.

I claim:—

1. A can adjusting or reshaping machine, 20 comprising an expansible core upon which the can is to be positioned, means by which the core may be expanded, a matrix consisting of hollow sections having corresponding ends closed and their other ends open, 25 and means carrying the matrix sections for movement into and out of contact with the side and bottom walls of the can on the core.

2. A can adjusting or reshaping machine, 30 comprising an expansible core upon which the can is to be positioned, means by which the core may be expanded, a sectional matrix, levers located at opposite sides of the core and carrying the matrix sections, and 35 means pivoting the levers for movement towards and away from the core in planes angularly related to the axis of the core so that the matrix sections may be moved into and out of contact with the can on the core.

40 3. A can adjusting or reshaping machine, comprising an expansible core upon which the can is to be positioned, means by which the core may be expanded, levers located at opposite sides of the core and extending forwardly and rearwardly beyond the core, a matrix embodying sections connected to intermediate portions of the levers, and means 45 pivoting the rear ends of the levers so that the levers may be moved toward and away from the core to move the matrix sections into and out of contact with the can on the core.

4. A can adjusting or reshaping machine, 50 comprising a table, an expansible core adapted to permit the can to be arranged thereon and consisting of sections slidably mounted on and extending upwardly from the table, the core sections having downwardly converging inner or opposing sides 55 and provided in said sides thereof with vertical passages, a downwardly tapering wedge arranged between said sides of the core sections, a bar having the wedge secured to the upper end thereof and arranged in said 60 passages, a lever arranged below and pivoted to

the table, means pivotally connecting the lower end of the bar to the lever, and a matrix adapted to surround the can during the expanding of the core.

5. A can adjusting or reshaping machine, 70 comprising a table provided with an opening having its wall rabbeted to provide an annular recess, an expansible core adapted to permit the can to be arranged thereon and consisting of sections provided at their lower ends with outwardly directed flanges resting and slidably mounted upon the horizontal wall of said recess, the core sections extending upwardly from the table and having downwardly converging inner or opposing sides, a retaining ring secured to the table and over-lying the core section flanges, a downwardly tapered wedge arranged between said sides of the core sections, a lever arranged below and pivoted to the table, 80 means connecting the wedge to the lever, and a matrix adapted to surround the can during the expanding of the core.

6. A can adjusting or reshaping machine, 85 comprising a table provided with a pivot support, an expansible core mounted on the table and adapted to permit the can to be arranged thereon, means by which the can may be expanded, a sectional matrix adapted to surround and contact with the major portion 90 of the side wall of the can during the expanding of the core, and levers pivotally and slidably connected to the support and carrying the matrix sections.

7. A can adjusting or reshaping machine, 95 comprising a table, a pivot support carried by the table, an expansible core mounted on the table and adapted to permit the can to be arranged thereon, means by which the core may be expanded, a sectional matrix adapted 100 to surround the can during the expanding of the core, the matrix sections being provided with recesses and grooves for the reception of the bottom bead of the can, and levers carrying the matrix sections and pivotally 105 and slidably connected to the support.

In testimony whereof I hereunto affix my signature.

ANDREW J. HOLLARS.
